UNITED STATES PATENT OFFICE.

LEE D. HAMACHER, OF KANSAS CITY, MISSOURI, ASSIGNOR TO HAMACHER-HAWKINS MANUFACTURING COMPANY, A CORPORATION OF MISSOURI.

LOOSE-LEAF BOOK.

1,020,948.

Specification of Letters Patent. Patented Mar. 19, 1912.

Application filed September 15, 1909. Serial No. 517,822.

To all whom it may concern:

Be it known that I, LEE D. HAMACHER, a citizen of the United States, residing at Kansas City, in the county of Jackson and State of Missouri, have invented certain new and useful Improvements in Loose-Leaf Books, of which the following is a specification.

My invention relates to improvements in loose-leaf books, and one important feature of the invention resides in the novel means for holding the hook-carrying members of the book in an open or a closed position.

Another feature of the invention resides in the novel manner in which the hooks of the book are secured to the hook-carrying members.

Referring to the accompanying drawing which illustrates the invention: Figure 1 represents a broken end view of my improved book. Fig. 2 is an enlarged cross section on line II-II of Fig. 4. Fig. 3 is a perspective view of the metal parts of the book ready to be assembled. Fig. 4 is a plan view of the book with the cover removed. Fig. 5 is a broken detail of one of the hook-carrying members. Fig. 6 is an edge view of one of the hooks.

In carrying out the invention I employ a frame 1, provided with longitudinal, in-turned, marginal flanges 2 forming grooves 3.

4 designates a pair of hook-carrying members rockingly mounted in the grooved portions of the frame, and provided at their reinforced ribbed portions 4^a with a plurality of hooks 5 which are substantially secured to the hook-carrying members without the use of solder. The lower end 6 of each hook is swaged, as shown in Fig. 6, to form a shoulder 7. The swaged end of the hook is passed through an aperture 8 provided therefor in its respective hook-carrying member, until shoulder 7 contacts with the upper surface of said member. The lower terminal of the hook is then upset to form a head 9 which clenches the underside of the hook-carrying member and draws the shoulder reliably into engagement with the upper side of said member so that the hook will be reliably secured thereto.

When opening and closing the hooks, they

are caused to operate in unison and held in the open or closed position, by a plurality of U-shaped members 10, the upper portions 11 of which overlap the adjacent portions of the hook-carrying members, while their lower terminals 12 underlap said hook-carrying members, thus when the hooks are opened the underlapping ends 12 will be brought into engagement with the underside of the hook-carrying members, and thereby limit the opening movement of the hooks. Members 10 are prevented from shifting longitudinally by their downturned portions 13 engaging the sides of a plurality of notches 14 extending inwardly from the adjacent edges of the hook-carrying members. Members 10 are rendered resilient by longitudinal slots 15, so that they will reliably hold the hook-carrying members seated in the grooved portions 3 of the frame, and also reliably hold the hooks in an open or a closed position.

16 designates a cover which is secured to the rear side of frame 1.

In practice when it is desired to insert or remove loose-leaves 17, the hooks 5 are grasped near their upper ends and drawn apart. This operation causes the hook-carrying members to rock upwardly until the underlapping ends 12 of the U-shaped members 10 engage said hook-carrying members, and thereby check further opening of the hooks. The closing movement of the hooks is limited by the ends thereof contacting with each other, as shown in Fig. 2.

When desired slots 15 may be omitted from members 10 when the latter are to be employed merely to limit the opening of the hooks and to cause the hook-carrying members to operate in unison, and when members 10 are so employed any of the well-known springs may be added to the book to obtain the requisite pressure for reliably holding the hooks open or closed.

Having thus described my invention, what I claim is:—

1. In a device of the character described, a frame, hook-carrying members rockingly-mounted therein and provided with inwardly-extending notches at their adjacent edges, and a plurality of slotted U-shaped members extending through the notches and

overlapping and underlapping the hook-carrying members.

2. In a device of the character described, a frame, a cover to which said frame is secured, hook-carrying members operably mounted in the frame and provided with notches at their adjacent edges, and a slotted resilient member extending through the

notches and overlapping and underlapping the hook-carrying members.

In testimony whereof I affix my signature, in the presence of two witnesses.

LEE D. HAMACHER.
